KEYBOARD PERFORATOR AND COUNTER

Edward S. Larson and Carl A. Levin, Chicago, Ill.,
assignors, by mesne assignments, to Teletype-
setter Corporation, a corporation of Delaware

Application April 27, 1935, Serial No. 18,574

17 Claims. (Cl. 164—112)

The present invention pertains to composing systems and apparatus therefor and particularly to perforators and counters for preparing a perforated strip for the automatic control of line 5 composing and casting machines.

Composing machines of the linecasting type are provided with matrices which consist of small brass units carrying indented characters or intaglios, and which vary in thickness according to 10 the width of the character impressed thereon. The length of a line of composed matter is dependent not only upon the number of matrices included in the line but also upon the cumulative thicknesses of the matrices composing the line. 15 During the preparation of a perforated strip representing lines of composed matter, it is necessary to totalize the various thicknesses of matrices corresponding to code perforations made in the strip, and translate the information upon an indicator to permit the operator to determine the 20 length of line remaining as each key is operated and thus judge the justifiability of the line.

Besides the usual character matrices, composing machines of the particular type to which the present invention relates are also provided with 25 expansible space bands which comprise a portion analogous to and having the contour of a character matrix and which are positioned in the line of matrices usually between successive 30 groups of character matrices representing words, and this portion has slidably articulated thereto and depending therefrom a wedge portion. By means of these wedge portions, the justifying 35 matrices are expanded or adjusted between certain ranges of thickness before the casting operation is performed. It is essential, therefore, that an indicator be provided which denotes not only the totalization of the character 40 matrices but also the expansibility of the space bands, that these two functions be performed simultaneously, and that the resultant effect be apparent to the operator at all times.

Matrices of the same style or font are stored 45 in a magazine, and these magazines are adapted to be utilized interchangeably in the composing machine. Corresponding matrices in the different fonts may vary in thickness; thus, lines of the same length but composed of a different 50 style or font of type will contain a different number of characters per line, which may require a different degree of justification.

The present invention has for its salient object 55 the provision of an extremely simple and compact counting device for counting cumulatively the widths of matrices of any font of type.

A principal feature of the invention resides in providing a keyboard perforator and counter having a readily removable and interchangeable code bar unit to render the counting device utilizable for totalizing incrementally the matrix 5 widths of any font of type.

To achieve the above and other objects of the invention, the keyboard perforator and counter according to Patent No. 2,059,250 granted November 3, 1936 to H. L. Krum is modified to accommodate an interchangeable code bar unit. Reference should be made to the patent for a full and comprehensive disclosure of the keyboard perforator and counter. In the embodiment disclosed herein, the keyboard includes key- 10 levers arranged in a manner characteristic of typewriters which operate, through a permutation selector mechanism contained in the housing of a perforator and counter apparatus, to position permutably a series of code discs of a selector to select one of a circumferentially arranged series of rods. A counting barrel to which a constant torque is imparted is provided with a circumferentially arranged series of slides, a selected one of which cooperates with the selected 15 rods to determine the degree of rotation of the counting barrel. The selector rods are sixteen in number, fourteen of which represent a series ranging from five units to eighteen units inclusive, since it is not necessary in practice to employ matrices smaller than five units in width. The remaining two rods are representative of the zero position and function respectively. Thus, as the stop member or counting barrel 20 is rotated through variable angles according to the selecting rod operated, like rotation is imparted to a spiral gear operatively associated with the counting barrel, and through a suitable gear train variable motion is imparted to a matrix pointed associated with an indicator dial. Hence, as the keys are depressed, the matrix 25 pointer is moved through variable cumulative distances corresponding to the widths or thicknesses of the matrices represented by the keys. The variable motion imparted to the matrix 30 pointer may be adjusted for different fonts of type by interposing between the keylevers and the selector mechanism for the counting device, an interchangeable code bar unit comprising a plurality of pairs of coded elements, one 35 pair allotted to each keylever and operable thereby.

A more comprehensive understanding of the present invention may be had from the following description, taken in conjunction with the ac- 40 45 50 55

companying drawings wherein like reference characters represent similar parts throughout the several views.

Fig. 1 is a perspective view of a perforator and counter with parts broken away showing the apparatus necessary for a clear understanding of the present invention;

Fig. 2 is a perspective view of the micrometer attachment shown only partly in Fig. 1;

Fig. 3 is a cross-sectional view taken through the code disc selector and longitudinally with respect to the selector bars to show the correlation between the selector mechanism and the interchangeable code bar unit;

Fig. 4 is a sectional view taken substantially on line 4—4 of Fig. 3, showing the code bar unit in the shift position;

Fig. 5 is a view similar to Fig. 4, showing the code bar unit in the unshift position;

Fig. 6 is a perspective view illustrating the adaptation of the present invention to the device shown in United States Patent No. 2,043,231, granted June 9, 1936 to S. Bracken et al.; and

Fig. 7 is a perspective view illustrating the spring retention means for the coded elements contained in the interchangeable code bar unit.

Having reference to Fig. 1, it is noted that most of the parts shown have their counterpart in the structure illustrated in Patent No. 2,059,250, the entire perforating mechanism not being shown but which is, nevertheless, considered as operatively associative with the present invention. In Fig. 1 a plurality of keylevers 11 are pivoted on a common rod 12 and are normally held by individual springs 13. These keylevers extend over a number of pairs of selector bars 14 and 15 included in the perforator selecting unit indicated generally by the numeral 16, and pairs of bars 17 and 18 included in the selecting unit of the counting mechanism indicated generally by the numeral 19. Each keylever 11 is arranged to depress one of the bars 14 or 15 of each pair of bars. Through the medium of rocker arms 21, the bar 14 or 15 lifts the other bar of the pair to reciprocate longitudinally a permutation bar 22 cooperatively associated with and subadjacently disposed to each pair of bars 14 and 15, to impart corresponding movement to the associated pivoted member 23. The members 23 as disclosed in Patent No. 2,059,250 control the operation of punch interference elements 24 in the tape perforating unit 25. The bars 22 are set in characteristic combinations, and for this purpose bars 14 and 15 are provided with notched upper edges, the bars of each pair being complements; that is, the high portions of one bar are disposed opposite to the low portions of the other bar of the same general pair.

Interposed between the series of keylevers 11 and the counter selector unit 19 is a removable and interchangeable code bar unit indicated generally by the numeral 26 which carries therein a plurality of pairs of coded elements 27. The present invention contemplates the substitution, for the single counting code levers 106 of Patent No. 2,059,250, of a pair of elements 27, one for upper case characters and the other for lower case characters. In this manner, a pair of counting code elements is provided which is slidable vertically in a common slot below each keylever, the two counting code elements being held together by means of dowel pins, one pin in each code bar or element. The designations 30 on the code elements 27, which represent the number of units, or the unit-group, to which the character

represented thereby belongs, are made in such manner that when the two code elements are assembled, the lower case count may be read on the face of the front bar nearest to the left end, and the upper case count may be observed on the face of the rear bar through the window or aperture in the front bar. The advantage of providing the counting code elements in pairs resides in the fact that these elements may be reversed end for end, either jointly or individually, and may thus be utilized in one position for upper case counts, and in reversed position for lower case counts. Further, the individual elements may be paired or combined indiscriminately one with another, and variably with respect to 15 different codes. Thus there is allotted to each of the keylevers 11 a pair of coded elements 27 which coat with the pairs of permutation bars 17 and 18 of the counter selecting unit 19.

The removable code bar unit 26 for carrying the pairs of coded elements 27 comprises a channel shaped member having a web portion 28 (Fig. 4), and side walls 29 and 31, which are in turn provided with flanges 32 and 33 respectively. The web 28 is provided with rectangular apertures 34 (Fig. 1) to guide the vertical projections 35 and 36 of the coded elements 27. The flanges 32 and 33 have notches in vertical alignment with the apertures 34 to insure the vertically guided movement of the coded elements 27.

The coded elements 27 are retained in their vertical or uppermost position by individual detent springs 37, each of which, as indicated in Fig. 7, comprises a coil spring having its extremities extended tangentially thereto and oppositely directed therefrom, which in turn terminate in laterally disposed portions 38 (Fig. 7) adapted to coat with the inner surfaces respectively of projections 35 and 36 of the coded elements 27. These springs 37 are mounted upon a rod 39 carried in the unit 26. A guide member 41 guides the extremities of the coil spring 37. With detent springs according to this arrangement, the code elements 27 are readily removable and insertable and are given a floating construction. To insert a pair of code elements 27, they need only be assembled by means of their dowel pins and slid up into the notches in flanges 32 and 33 and into the corresponding apertures 34 until portions 38 of the spring engage the undercut portions of projections 35 and 36, the spring then acting to urge the pair of elements 27 upwardly against the depending flanges of member 41. The pair of elements 27 is readily removable by urging the pair downwardly under slight pressure, thus flexing the tangentially extended portions of spring 37 until the ends 38 thereof slip over the inner apical portions of projections 35 and 36 of the code elements 27.

A shiftable carrier or cradle indicated generally by the numeral 42 (Fig. 4) controls the movement of the removable code bar unit 26 from shift to unshift position and vice versa. Carrier 42 comprises a bottom plate 43 having depending ends 44 with slots 45 to engage rollers 46 carried on 65 studs 47 secured to a guide comb bar 48 (Figs. 1 and 3) of the counter selector mechanism 19. Mounted upon and secured to the bottom plate 43 are a pair of Z-shaped members 49 and 51 which together with plate 43 form a track or runway for 70 the code bar unit 26. Thus, the code bar unit 26 is movable endwise, or transversely with respect to the keylevers.

The shifting of the code bar unit 26 from unshift to shift position and vice versa is controlled 75

by a shift bail 52 operated by the shift keylever 53 and the unshift keylever 54 (Fig. 1). Keylevers 53 and 54, like the keylevers 11, are pivotally mounted on rod 12. Associated with the shift keylever 53 is a lever 55 pivoted at 56 to bracket 57 carried on the under side of the base portion or housing 58. The extremity of lever 55 associated with the keylever 53 terminates in an abutting portion 59, and adjacent to portion 59 are two vertically extending projections 61 and 62 (Fig. 4) which are oppositely deflected so as to embrace the keylever 53 to act as a guide therefor. The opposite extremity of lever 55 is pivotally connected to a link 63 (Fig. 1) connected to bracket 64 secured to the bail 52. Therefore, when the keylever 53 is depressed, the lever 55 will be rotated in a counterclockwise direction (as viewed in Fig. 1) to rotate, in turn, through links 63, bail 52 in a clockwise direction about its trunnion 65. This movement of bail 52 will cause, through a pair of links 66, the carrier 42 to shift toward the left (as viewed in Fig. 4), which is the shift position of the code bar unit 26.

Similarly, unshift keylever 54 is carried on pivot rod 12 and has associated therewith a lever 67 pivoted at 68 to a bracket 69 carried by the base portion 58. The end of the lever 67 contiguous to the key lever 54 is constructed in the same manner as the corresponding end of lever 55. The rearward end of lever 67 is connected to a link 71 which in turn is connected to a bracket 72 secured to bail 52. Therefore, when the lever 54 is depressed, counterclockwise motion is imparted to lever 67, which imparts, through link 71, counterclockwise motion to bail 52. Through links 66, the carrier 42, and hence code bar unit 26, is shifted toward the right as viewed in Fig. 4 to the unshift position.

Carried on the bail 52 (Fig. 1) is an arm 73 which cooperates with a detent member 74 mounted on a bracket 75. Member 74 is in the form of a bell crank lever, one arm of which carries a roller 76 coacting with a restraining projection 77 integral with arm 73, and the other arm of lever 74 is connected to a spring 78. By virtue of this detent means, the bail 52, and hence the code bar unit 26, will be retained in its shift or unshift position until actuated to its opposite position.

In the embodiment shown in Figs. 1 and 4, there is contemplated a counter selector mechanism adapted to a four-unit code, which, as set forth in Patent No. 2,059,250, is sufficient to embrace all of the permuted combinations required for the groups represented by six to eighteen unit thicknesses, inclusively. However, as will more fully appear hereinafter, the modification shown in Fig. 6 contemplates the employment of a five-unit code, for the reason, as indicated in Patent No. 2,043,231, that an extra element is necessary to control the auxiliary counting device interposed in the gear train between the aforementioned counting barrel 96 and the matrix pointer 111.

Subjacently disposed to each pair of selector bars 17 and 18 is a permutation bar 79 which is operatively related thereto through the medium of rocker arms 81 (Fig. 3) located near each extremity of the selector bars 17 and 18. These rocker arms 81, like rocker arms 21, are disposed in such manner that the depression of one selector bar of each pair of bars 17 and 18 causes the operation of the other bar of that pair in a reverse direction, and causes the bar 79 to be recipro-

cated longitudinally upon the alternate actuations of said pair of bars.

When any keylever 11 is depressed, the selector bars 17 and 18 will be moved in accordance with the location of the projections 40 on the code elements 27 to cause the movement of the permutation bars 79 in varying permutations. As indicated in Fig. 4, the code projections 40 on one of the elements 27 are effective in one shift position and the projections 40 of the other element 27 of the pair are effective in another shift position. The cradle 42 is shown in Fig. 4 in its left-hand or shift position, in which position the projections 40 of the rear element 27 are observed as being in cooperative relation with the bars 18 of the pairs of selector bars 17 and 18. In the position shown, the projections 40 on the front element 27 are observed as being out of cooperative relation with bars 17 and 18. When the cradle 42 is moved to the unshift position shown in Fig. 5, the projections 40 on the front element 27 are disposed in cooperative relation with the bars 17 and 18 and the projections on the rear element 27 are out of cooperative relation with bars 17 and 18. Moreover, the front counting code element 27 (which, as indicated, is an eighteen unit element) is provided with projections 40 which are non-cooperative in the shift position in Fig. 4 with either of the selector bars 17 or 18. But in the unshift position shown in Fig. 5, the first two projections 40 of the front element 27 (counting from the left), are cooperative with the bars 18 of the corresponding first two pairs of selector bars 17 and 18, and the next two projections 40 are cooperative with the bars 17 of the third and fourth pairs of bars 17 and 18. In connection with the projections 40 on the rear bar 27 (which in the instance shown represents a fourteen-unit element), these projections, in the shift position shown in Fig. 4, are cooperative with the bars 18 of each of the pairs of selector bars 17 and 18; and of course in the unshift position shown in Fig. 7, the projections 40 are not cooperative with any of the selector bars 17 and 18. These bars 79 are, as clearly described in Patent No. 2,059,250, operatively connected with a corresponding series of Y-shaped members 82 (Fig. 3) which will be positioned in accordance with the operation of the permutation bars 79, and will control the setting of a plurality of notched discs 83, forming a part of code disc selector indicated generally by the numeral 80.

Individual to each of the members 82 and notched code discs 83 is a transfer lever 84 which is pivotally mounted on a rod 85 journaled in a bracket 86 which is rocked through the co-action of cam follower 87 and operating cam 88 mounted on the operating shaft 89, in a manner described in said patent, to reciprocate the transfer levers 84 vertically. The cam 88 mounted on shaft 89 is provided with two symmetrical apices to permit a complete cyclic operation of the bracket 86 and levers 84 for each one-half revolution of shaft 89 and cam 88. For each operation of the bracket 86 carrying the transfer levers 84 the latter will be moved into operative relation with the Y-shaped levers 82; that is, whether the members 82 are swung to the right or left as viewed in Fig. 1, the transfer levers 84 will engage or be free of the upper end of Y-shaped members 82 to cause the discs 83 to be rocked in either a clockwise or a counterclockwise direction. With the Y-shaped members 82 operated in varying permutations in accordance with the movement of the permutation 75

bars 79, the discs 83 will likewise be rotated in varying permutations and will correspondingly cause the alignment of the various groups of notches formed in the periphery of the discs.

5 Cooperating with the notches in the discs 83 is a plurality of rods 91, there being a rod individual to each set of notches (when aligned) and arranged with anti-friction rollers 92. Each of the rods 91 is centripetally biased by an individual spring 93. In this manner the rods 91 normally tend to move radially toward a common center into the notches of the disc 83, but inasmuch as the notches are arranged so that for each setting of the discs only one group thereof will be in transverse alignment, only one of the rods 91 at a time will be moved into the notches. Also, the notches in the disc 83 are arranged so that when the discs are moved for a subsequent selection, the previously selected rod 91 will be cammed outwardly against the action of its associated spring 93. Operatively secured to the right-hand end of each of the rods 91 is a stop member 94 (Fig. 1) which slides in suitable slots formed in a circular member 95.

25 To the right of the code disc selector 80 (as viewed in Fig. 1) is a counting barrel or unit 96, forming a part of the counting mechanism, which is rotated by power communicated from a continuously rotating motor (not shown) 30 through a friction clutch 97. The counting unit 96 comprises a plurality of circumferentially arranged slides 98 which are longitudinally slideable and adapted to coact with the stop members 94 to determine the degree of rotation of unit 96, 35 and any of the slides 98 which are found in the zero position are operated invariably by a lever (not shown), while a previously operated slide is simultaneously restored to its normal or non-operated position by a collar 99 to accomplish 40 through the coaction of an operated slide 98 and a selected stop member 94, the incrementally progressive movement of the counting unit 96. The counting unit 96 includes a shaft 101 on which is formed a worm 102. Attention is directed herein to the structural feature of counting unit 96 in that it is of a very small diameter, thereby permitting of a high speed of rotation. By having the parts near the axis of rotation, the centrifugal action is reduced and the moment 50 of inertia is materially less, which makes possible the rotation of the parts at very high speeds.

55 As previously mentioned, the slides 98 cooperate with the rods 91 to arrest the rotation of the counting unit 96 which is driven through a friction clutch 97 to cause a corresponding degree of rotation to worm 102. The rotation of the worm 102 which meshes with a gear 103 secured to a shaft 104 causes the corresponding angular rotation of a shaft 105 through gears 60 106 and 107. A worm 108 is fixed to the right extremity of shaft 105 and is adapted to mesh with a worm wheel 109 associated with a matrix pointer 111, completing a gear train between the counting unit 96 and the matrix pointer 111.

65 As shown in Fig. 1, the indicator comprises a portion 112 adapted to carry slidably thereon a dial 113 provided adjacent its arcuate edge with a scale or series of graduations representing the number of ems in a line of maximum length. 70 The reverted end of the matrix pointer 111 moves along this edge of the dial from left to right, towards zero, in response to the totalization of the matrix thicknesses by the counting mechanism. Thus, the distance from the pointer 111 to zero 75 indicates the amount of space left in the line to

be filled with matrices when the line contains no space bands. However, when space bands are inserted in the line, the space remaining to be filled varies with the number of space bands inserted. So, to indicate the justifiability of the 5 composed line, a pair of space band pointers 114 and 115 are provided, the distance between the pointers 114 and 115 indicating the amount of expansibility of the space bands.

10 In the embodiment shown, the dial 113 is articulated to the minimum space band pointer 115 through pin 116 and is movable with said pointer. The space left in the line to be filled when space bands are inserted is represented by the distance between the matrix pointer 111 and 15 any point between space band pointers 114 and 115. The manner of effecting the differential or proportional movement of pointers 114 and 115 toward the left (from the zero position) is fully set forth in Patent No. 2,059,250 and need not 20 be reiterated here. The matrix pointer 111, as shown in Fig. 1, is disposed between a flanged sleeve 117, carrying gear 109 and a disc 118, and as fully described in said patent, the matrix pointer 111 is rendered movable with the gear 25 109 by reason of the frictional resistance generated between it and the disc 118 by a spring 119 through rod 121. To effect the return of the matrix pointer leftwardly (as viewed in Fig. 1) to its initial or beginning-of-line position 30 against a stop (not shown), the rod 121 integrally formed with disc 118 is pushed forwardly by a suitable means against the compressive action of spring 119 to suspend the holding action of member 119 and permit matrix pointer 111 35 to be returned to its initial position by a spring 122 acting on a cord 123.

40 Fixed to shaft 105 is a gear 124 (Figs. 1 and 2) adapted to mesh with a spiral gear 125 fixed to a shaft 126, which as shown in Fig. 2, has secured to its upper extremity a units pointer 127 which cooperates with a units scale or micrometer 128. The scale 128 is rotatably carried on a bracket 129 mounted on the base 58. Also carried by the bracket 129 is a tubing 131 for supporting the 45 shaft 126. The scale 128 is rotatable manually in either direction independently of the pointer 127 by means of a handle 132.

45 Referring again to Fig. 1, the gear 124 is rotated in unison with gear 107 and to the same 50 angular extents. Since the unit movement of the matrix pointer 111 along the arcuate edge of scale 113 can only be estimated between the smallest subdivisions shown on the scale 113, the function of the micrometer scale 128 will be 55 apparent. Each subdivision on the scale 128 represents one unit; thus for a matrix thickness count of eight units, for example, the pointer 127 will rotate in a clockwise direction (as viewed in Fig. 2) a distance equal to eight 60 such subdivisions. To facilitate the reading of the movement of pointer 127 accurately, the scale 128 is rendered movable by means of handle 132, so that before a counting operation is initiated by the depression of a keylever, the 65 scale 128 is rotated so as to align one of the graduations with the pointer 127. Then as a key is operated, the movement of the pointers 111 and 127 in units can be accurately ascertained.

Modification

70 As previously alluded to, the modified embodiment of the invention as illustrated in Fig. 6 contemplates the utilization of an auxiliary counting device such as disclosed in Patent No. 75

2,043,231, and the addition of another pair of selector bars 141 and 142 to control the operation of the auxiliary counting device, which is indicated generally by numeral 143.

5 Briefly, the auxiliary counting device 143, as set forth in said Patent No. 2,043,231, comprises a differential device for adding an invariable and definite increment to selected ones of the unit measurements of a variable nature controlled by 10 the counting mechanism 96. As pointed out in Patent No. 2,043,231, the differential device 143 in its entirety is substituted for the gear 107 (Fig. 1). Gear 144 thereof (Fig. 6), which is analogous to gear 107, is loosely mounted on shaft 105, and has affixed thereto, by means of studs 145, an internal gear 146. Also loosely mounted 15 on the shaft 105 is a ratchet wheel 147 which carries a pair of planetary gears or pinions 148 (only one of which is shown) diametrically opposed to each other and in mesh with a gear 149 fixed to and concentric with both the shaft 105 and the internal gear 146.

Associated with ratchet wheel 147 is a pawl 151 pivotally carried at the extremity of one arm 25 of a lever 152 (Fig. 6) loosely mounted on shaft 105. A spring actuated detent member 153 is provided for ratchet wheel 147. Pawl 151 is normally urged into coaction with ratchet wheel 147 by a spring 154 distended between a spring post 30 secured to the pawl 151 and a spring post secured to lever 152. Pawl 151 and the arm of lever 152 on which it is carried are actuated, as will presently appear, by an extension 155 on the spacer bail or bell crank 156.

35 Depending from the pivot 157, which is also common to pawl 151, is an arm 158 having near its lower extremity a slot in which operates a stud 159 carried on a slidable member 161. Member 161 is slidably carried on a pair of studs 162 secured to a bracket (not shown) mounted on the base 58. Arm 158 is also provided with a shouldered portion 163 which cooperates with the extremity of arm 155 so that when the arm 158 is actuated to bring shoulder 163 into 40 operation with arm 155, the arm 155 as it is oscillated will cause a downward movement of pawl 151 to rotate the ratchet 147 through an angular distance of one tooth.

The lower edge of member 161 is provided with 50 a pair of spaced depending projections adapted to embrace arm 164 of a bell crank lever 165, the other arm of which is pivotally connected to a link 166 extending from said arm to a lever 167 carried on the pivot shaft common to the Y-shaped levers 82. The lower end of lever 167 is articulated to a permutation bar 168 sub- 55 jacently disposed to and associated with the pair of selector bars 141 and 142 through a rocker member 169. The actuation of bars 141 and 142 by means of the keylever 11 through a coded element 27 having a code projection therefor will cause, through rocker arm 169, the longitudinal reciprocation of permutation bar 168, depending upon whether or not it is desired to operate the auxiliary counting device. When it is desired 60 to do so, the bar 141 is depressed to the position shown in Fig. 6, whereupon the permutation bar 168 has assumed its rightward position and lever 167 its counterclockwise position, link 166 its 65 leftward position, bell crank 165 its counterclockwise position, and slide 161 and arm 158 their rightward position, bringing shoulder 163 beneath arm 155. As is disclosed in Patent No. 2,043,231, the keylever operates, simultaneously 70 with the operation of the selector bars of the

selector mechanism 19, a universal bar (not shown) which trips a clutch to initiate the rotation of an operating shaft 89 which is permitted to make one-half revolution, the cam 172 thereon acting to oscillate the bail 156 and hence impart downward movement to arm 155 which in turn, through arm 158 and pawl 151, rotates the ratchet 147 through a distance equivalent to one tooth.

As also indicated in Patent No. 2,043,231, the 10 rotation of gear 149 and shaft 105 and consequently the movement of matrix pointer 111 is dually controlled, in one instance by the counting unit 96 and in the other by the combined effect of the counting unit 96 and ratchet wheel 15 147. For a description of the detailed operation of the combined actions of the primary counting device 96 and the auxiliary counting device 143, reference should be had to Patent No. 2,043,231 since the detailed structure of said devices is not a part of the present invention, the present invention having reference to the interchangeable code bar means for actuating the selector bars in the counting mechanism 19 to control the operation of said devices. 25

As indicated in Figs. 1 and 3, a latching means is provided for retaining the interchangeable code bar unit 26 in its set or home position. In the embodiment disclosed, this latching means comprises a series of depending projections, formed 30 integral with the right end of web 28 (as viewed in Fig. 1), and includes a pair of spaced depending portions 182 and 183 adapted to be digitally manipulated, and an intermediate latching portion 184 adapted to cooperate with a latch 185 35 in the form of a bell crank lever pivoted at 186 and acted upon by a spring 187 (Fig. 3). Latch 185 is mounted in a housing 188 secured to the portion 44 of the carrier 42. The particular advantage of this structure resides in permitting 40 the ready removal of the code bar unit 26 by engaging the portions 182 and 183 with two non-adjacent fingers, and the convenient manipulation of the latch 185 by the intermediate finger to impart to said latch slight downward pressure to 45 unlatch the same.

Inasmuch as numerous changes and modifications may be made without departing from the spirit and scope of the present invention, it is not intended that this invention be limited to 50 the specific language of the foregoing description nor to the details of the accompanying drawings, but to be permitted instead a latitude of construction as indicated by the hereunto appended claims. 55

What is claimed is:

1. In combination with a device for producing strips to control composing machines, a plurality of keylevers, a selecting mechanism operable in accordance with the operation of said keylevers 60 comprising a detachable and interchangeable code bar unit provided with a plurality of pairs of coded elements selectively and operatively related thereto, means facilitating the pairing indiscriminately of said elements, and means facilitating 65 the insertion of interchangeable units.
2. In combination with a device for producing strips to control composing machines, a plurality of keylevers, a selecting mechanism operable in accordance with the operation of said keylevers 70 comprising a detachable and interchangeable code bar unit provided with a plurality of pairs of coded elements selectively and operably related thereto, means facilitating the pairing indiscriminately of said elements, individual spring latch 75

means for controlling the operativeness of each pair of elements, and means facilitating the insertion of interchangeable units.

3. In a keyboard device for making impressions on a tape to represent successive lines made up of characters of different widths, a series of keys, means for totalizing the thicknesses of the characters in a line, a selector mechanism individual to said means, and a pair of reversible and selectively combinable code members individual to each key, each member of said pair effective under predetermined conditions to selectively operate the selector mechanism.

4. In a keyboard device, a series of keylevers, mechanism adapted to be controlled by said keylevers, a pair of floating elements associated with each keylever, and means controlled by certain of said keylevers to render one or the other of said pair of elements effective to control said mechanism differently in accordance with the condition of said means.

5. In a keyboard apparatus, a series of keys, a counting mechanism comprising means to totalize variable additive amounts and to indicate continuously such totalizations, a unit carrying a plurality of pairs of code elements, means to control the operation of the counting mechanism according to one or the other of said elements, said code bar unit being adapted to be interchangeably insertable in the apparatus for interchange according to the font of type to be used, operative connection between the keys and said unit such that the code elements may be operated in a plurality of ways for each key, and means to select the way in which the code element is to be operated.

6. In a keyboard perforator, a perforating device, a counting device, selector mechanisms individual to each of said devices, a plurality of keylevers, a corresponding plurality of pairs of code elements, one pair associated with each keylever, a pair of special keylevers, means controlled by the alternate operation of said special keylevers to move the pairs of code elements collectively and simultaneously to either of two positions whereby said perforating device is operated invariably in the same manner, and said counting device can be operated in either of two different manners, depending on which element of the pair of elements is operative.

7. In a keyboard perforator, a perforating device, a counting device, selector mechanisms individual to each of said devices, a plurality of keylevers, a corresponding plurality of pairs of code elements disposed parallel to said keylevers and adapted to operate the selector mechanism individual to the counting device, and means to move said pairs of elements in unison to either of two positions so that said perforating device is operated invariably in the same manner and said counting device is operated in either of two different manners depending on which element of the pair of elements is operative.

8. In an apparatus for preparing a record to be used to control line composing machines, a perforating mechanism, a counting mechanism, a group of transversely superpositioned keylevers and combination bars for controlling said perforating mechanism, the combination of another group of paired elements having coded projections and bars for actuating the counting mechanism, and means for effecting a relative shifting movement between the coded elements and the bars whereby the counting mechanism may be operated variably according to one or the other

element of each pair of elements while the perforating mechanism is operated invariably in the same manner.

9. In an apparatus for preparing a record to be used to control line composing machines, a perforating mechanism, a counting mechanism, a group of transversely superpositioned keylevers and combination bars for controlling said perforating mechanism, the combination of a group of paired elements having coded projections and bars for actuating the counting mechanism, and means for effecting a relative shifting movement between the coded elements and the bars whereby the counting mechanism may be directly operated by said keylevers variably according to one or the other element of each pair of elements while the perforating mechanism is operated invariably in the same manner.

10. In a keyboard apparatus, a plurality of sets of selectable elements, keylevers for operating said elements in different permutations, signal controlling means operated by one of the sets of elements, a counting mechanism controlled by the other set of elements through the instrumentality of a plurality of pairs of coded elements removably insertable collectively between said keylevers and said other set of elements, said counting mechanism including a code disc selecting device operable permutably, a series of members, one selected for each operation of said device, a counter, and means responsive to each operation of a keylever in cooperation with said selected member for determining the extent of operation of the counter.

11. In a keyboard perforator for making perforations in a tape to represent successive lines made up of characters of different widths, a series of keys, means for totalizing the thicknesses of the characters in a line, a selector mechanism individual to said means, means controlled by said totalizing means to indicate the cumulative thicknesses of the characters, a micrometer scale adjustable to indicate individual totalizing operations, and code members individual to each key effective under predetermined conditions to selectively operate the selector mechanism to actuate simultaneously said indicating means and said micrometer scale.

12. In a keyboard perforator for making perforations in a tape to represent successive lines made up of characters of different widths, a series of keys, means for totalizing the thicknesses of the characters in a line, a selector mechanism individual to said means, means controlled by said totalizing means to indicate the cumulative thicknesses of the characters, a micrometer scale adjustable to indicate individual totalizing operations, and a pair of code members individual to each key, each member of said pair effective under predetermined conditions to selectively operate the selector mechanism to actuate simultaneously said indicating means and said micrometer scale.

13. In a device for preparing control strips for the control of linecasting machines, means for applying to said control strips indicia representing characters of varying widths, a counting mechanism, an indicating mechanism controlled by said counting mechanism, and a micrometer indicator also controlled by said counting mechanism simultaneously with its control of said indicating mechanism.

14. In a device for preparing control strips for the control of linecasting machines, means for

applying to said control strips indicia representing characters of varying widths, counting means, indicating means controlled by said counting means, and a micrometer indicator adjustable to indicate individual totalizing operations and controlled by said counting means simultaneously with its control of said indicating means.

15. In a device for preparing control strips for the control of linecasting machines, means for applying to said control strips indicia representing characters of varying widths, counting means, an indicating mechanism controlled by said counting means, and a units indicator also controlled by said counting mechanism simultaneously with its control of said indicating means.

16. In a device for preparing control strips for the control of linecasting machines, means for applying to said control strips indicia representing characters of varying widths, counting means,

an indicating means controlled by said counting means; and a micrometer indicator also controlled by said counting mechanism simultaneously with its control of said indicating mechanism, said micrometer indicator having the scale thereof adjustable to designate any indication as a zero indication.

17. In a device for preparing control strips for the control of linecasting machines, means for applying to said control strips indicia representing characters of varying widths, counting means, an indicating means controlled by said counting means, and a micrometer indicator also controlled by said counting mechanism comprising a rotatable pointer and a scale adjustable with respect to said pointer to permit any portion of the scale to be brought into registry with the pointer.

EDWARD S. LARSON.
